CAPACITY CONTROL FOR STEAM GENERATORS

John V. Pyle, Briar Cliff Manor, N. Y., assignor to
Kennedy-Van Saun Mfg. & Eng. Corp., New
York, N. Y., a corporation of Delaware

Application January 9, 1948, Serial No. 1,437

8 Claims. (Cl. 236—26)

1

My invention relates to improvements in controlling the capacity of steam generators, and to a pressure operated control which cooperates in a particular manner with the upper and lower portions of a steam generating unit.

One of the problems encountered in connection with steam generating units which include furnaces having water cooled walls is that tube failures have occurred in such walls. Various theories have been advanced for the cause of furnace tube failures in steam generators. Furthermore, these failures result in very high losses not only from the damage done to the plant but also because of the shut-down time and repairs necessary. Insurance claims of many kinds also arise.

In cases where furnace tubes have failed in large steam generator furnaces, and insurance claims have been filed and paid, the damaged plant is usually inspected along with its records. Such records almost invariably show that the water level in the steam and water drum was at normal when the tube failure occurred, thus indicating that there was no lack of water in the unit or negligence in supplying water thereto.

Steam generating units of the type in question have a furnace structure which includes vertical wall tubes terminating at the top and bottom in headers, the upper of which discharge through connecting tubes into a steam and water drum at the top of the unit. The lower headers are supplied with water by tubes connected thereto from a drum in the lower part of the furnace which in turn is supplied with water by downcomers from the steam and water drum. The tubes between the lower drum or header and the lower headers for the wall tubes are known as "feeder tubes," and according to standard practice one feeder tube is provided to supply water for from five to ten wall tubes in the furnace. It is generally believed that the high velocity of the steam and bubbles in the wall tubes applies a suction to the feeder tubes so as to draw water into the wall tubes and keep them continuously supplied.

With furnaces of the type referred to, it is generally the practice, if possible, to keep the capacity as high as possible, but it will be apparent that even though the operator has a water level gauge on the steam and water drum, and knows that he has a normal water level therein, he still does not know and has no means for determining when steaming capacity of the furnace tubes has been reached. According to my understanding of the problems discussed above, a point is reached in the operation where the capacity to

5 supply water to the lower portion of the steaming tubes is exceeded and that consequently some of the tubes which are starved of water become so hot that they fail. It should be understood that the temperatures generated in the combustion chambers of such steam generating units run in the neighborhood of from 2300° to 2700° F.

10 My understanding of the tube failures in steam generators of this type and the reason why tubes fail in the furnace chamber, is that in most, if not all cases, the failure is due to operating the unit above safe steaming capacity of the wall tubes of the furnace combustion chamber, at least some of them. While with present equipment it is almost impossible to determine when the limit of steaming capacity is reached it is my conclusion that the tubes in certain places become starved or deprived of sufficient water, because for one reason or another water cannot be supplied fast enough through the headers and feeder tubes provided, at the operating capacity.

15 My primary object of my invention is therefore to control the unit capacity and provide an improved control which will indicate to the operator the condition of water supply in the lower headers in the steam generating unit.

20 In accordance with an important feature of my invention I provide a pressure indicator connected up with the steam and water drum and adapted to indicate the pressure therein. A pressure indicator is also connected up to all of the lower headers in the unit so as to indicate the pressures therein. A preferred form of pressure indicator is arranged to show at a glance the difference between the pressure in the steam and water drum and that in a particular lower header of the generator. I also advantageously provide an alarm or signal associated with the pressure indicator which will be operated when the pressure in a lower header approaches within a predetermined value of that in the steam and water drum.

25 I advantageously control the operation of a steam generator to avoid starving any of the furnace tubes, by controlling the firing and capacity of the generator in accordance with a comparison of the pressure in a lower header with that on the generator, and decreasing the firing rate when the pressure in the lower header approaches within a predetermined value of the pressure on the generator.

30 In large steam generator installations of the type under consideration, the head of water which would normally be maintained in such a unit may be in excess of 30 to 40 feet between

one of the lower headers and the water level in the steam and water drum. My improved apparatus is therefore based upon the idea of utilizing the difference in pressure between these points due to the hydrostatic head of water. When the unit is operated at a normal safe capacity the pressure in the lower header will be greater than that in the steam and water drum by the pressure due to the weight of the column of water. If the operator finds that the pressure in the lower header begins to approach that in the steam and water drum, he will know the unit is being operated in excess of its safe capacity, even if at the same time his gauge shows plenty of water in the drum. The operator therefore must adjust the unit to bring it out of the danger zone, for example, by reducing the firing rate.

My invention includes other features and advantages which will be described in greater detail hereinafter in connection with the accompanying drawing forming a part of this application.

In the drawings:

Fig. 1 is a vertical broken view partly in section, showing a portion of a steam generating unit in connection with which my invention is shown and illustrated diagrammatically.

Fig. 2 is a sectional view on an enlarged scale of one of the pressure responsive cylinders shown in Fig. 1.

Referring to the drawings, the steam generator shown includes a portion of the side wall built in connection with the structural steel members 10, 12 and 14. The unit includes a steam and water drum 16 at the top of the unit and water drum 18 at the bottom, these drums being connected by a pair of downcomer pipes 20 for flow of water from the ends of the drum 16 to the ends of the drum 18. The large pipes 20 are outside the furnace or combustion chamber which is indicated at 22.

The combustion chamber is defined by a side wall 24 including closely mounted radiation steaming tubes 26 extending between headers 28 and 30. Water is supplied to the header 28 from the drum 18 through feeder tubes 32, connected into distributed points along the drum 18. Steam and water are discharged from the header 28 into the drum 16 through tubes 34, in the usual manner.

The far end wall of the combustion chamber 22 includes closely mounted radiation steaming tubes 36 extending between headers 38 and 40. Water is supplied from the drum 18 to the header 38 through spaced groups of feeder tubes 42, while steam and water flow from the header 40 into the drum 16 through tubes 44.

In the particular generator unit illustrated, a tube wall is provided at the near end of the combustion chamber 22 by installing a row of radiation wall tubes 46 extending directly between drums 16 and 18. The tubes 46 at the lower portion of this tube wall are bent out of alignment in a conventional manner so that combustion gases produced in the combustion chamber 22 pass through the lower portion of the wall to contact superheater and economizer tube banks (not shown) in a known manner. In the generator structure as shown, the headers 28, 30, 38 and 40 and the ends of the tubes connected thereto are covered in the combustion chamber by fire brick or other refractory material 47, as indicated.

The steam and water drum 16 is provided with a liquid level gauge 48 and in accordance with

the features of my invention, this drum is connected by a line 50 to a pressure gauge or indicator 52. The line 50 connects into the steam space of the steam and water drum 16 so that the normal pressure maintained on the generator is transmitted through the line 50 to the pressure gauge or indicator 52. Water is supplied to the generator in accordance with the usual practice and introduced, preferably in a pre-heated state, into the steam and water drum 16 to maintain the desired water level therein, as indicated by the gauge 48. The instrument 52 may be located above the generator to provide drainage in the line 50.

The pressure gauge 52 comprises a part of the mechanism for controlling the capacity of the generator and for preventing the blowout of radiant wall tubes in the combustion chamber. The mechanism shown is merely diagrammatic, and the means shown for indicating the pressure in the steam space of the steam and water drum 16 includes a pointer or hand 54, a scale 56 and an operating cylinder 58. The hand 54 is pivoted on a shaft 59 and includes a pinion hub 60 operated by a rack 62, as shown more in detail in Fig. 2. In this view the pressure medium acting in the line 50 operates against a spring-loaded piston 64 in the cylinder 58. The rack 62 is connected in the manner shown to the piston 64, so that any variations in the pressure in the line 50 will effect movement of the hand 54 with respect to the scale 56 which is calibrated to indicate the pressures in pounds per square inch in the generator.

The gauge or indicator 52 includes another pressure indicator hand 66, a part of which is made of insulating material and shown in black. This hand has a pinion hub 68 which is pivoted on the shaft 59. The hub 68 is operated by a pressure cylinder arrangement 70 like that shown in Fig. 2. A pressure line 72 connects into the cylinder 70 and is in turn connected into branch lines 74, 76 and 78, having valves 75, 77 and 79, which are respectively connected into headers 38 and 30 and water drum 18. Since the pressure line 72 connects into the lower part of the unit and a substantial head of water is normally maintained therein, the pressure indicated by the hand 66 will be substantially above that indicated by the hand 54. Provision is made for selectively connecting up headers 30, 38 and water drum 18, and it will be understood that the pressure as registered when these different levels in the generator are connected up, will be different, due to the differences between the heights of the water columns involved.

The indicator 52 is advantageously connected up to an alarm or a generator control, or both. Accordingly, in the illustrated embodiment, the hand 54 is provided with a contact member 80 while the hand 66 has a similar contact member 82. The member 80 is connected through a wire 84, to an alarm 86, illustrated as a gong or bell, while the member 82 is connected by a wire 88 to a battery 90, which in turn is connected to the alarm 86. Wires 92 also connect up a control 94 with the contact members 80 and 82, through wires 84 and 88, and wires 96 lead to a motor or other control mechanism 98 for the steam generator, which is particularly adapted to reduce its capacity or output, such as combustion control. The control mechanism 98, for example, may operate a control valve 100 in a fuel supply duct 102 leading to the generator burners (not shown).

In the operation of large generators of the type illustrated, it may be extremely difficult or impossible without the applicant's invention to determine what part of the apparatus would first reach its safe capacity limit. In a given operation, where the output of the generator is gradually increased, either one of the headers 30 or 38 may be first to be starved of water. The lines 74 and 76 may be selectively cut into the line 72 at different ratings to obtain an indication by the position of the hand 66 with respect to the hand 54. The nearer the hand 66 approaches the hand 54, the lower the water supply to the particular header. The hand 66 is mounted slightly in front of the hand 54 and the contacts 80 and 82 are advantageously arranged so that when the hand 66 approaches to within a predetermined distance or pressure, for example five pounds of the pressure shown by the hand 54, for a generator of the size described, the contact 82 will engage the contact 80 and set off the alarm 86, and, if desired, put in operation the capacity reducing control 94. The instrument may include a hand for each lower header and for drum 18.

Since the water supplied to the headers 30, 38, and others in the lower portion of the generator must come from the water drum 18, a small movement of the hand 66 toward the hand 54 from its normal spacing therefrom, when the drum 18 is connected up, will indicate an approaching more serious water shortage in the headers 30, 38 and others supplied by the drum 18. Therefore, the instrument 52, may, if desired, include a special indicating hand which is separately connected up to the drum 18 and which would give a signal or actuate the control 94, or both. However, if a slight shortage of water, accompanied by a lower pressure in the drum 18, should occur, there would be at almost the same time, a more serious shortage in the headers 30, 38, and others in the lower part of the generator. The indicator, therefore, will in most cases, give proper protection if connected into one of these headers.

After trial runs on a generator with the indicator apparatus installed, the operator will know which header or headers first become starved of water as the output of the generator is increased. Such header or headers may thereafter be kept continuously connected into the pressure line 72.

It will be understood that the examples described above are merely illustrative and that the apparatus is diagrammatic. The pressure piping for the indicator 52 may include a sealed hydraulic system which has branch lines responsive respectively to the pressure in the drum 18 and in the headers in the lower part of the generator, while another line, 50, is responsive to the steam pressure in the drum 16.

What I claim is:

1. In an apparatus for controlling the capacity of steam generators having combustion chamber walls which include long bare radiation steaming tubes connected into headers in the lower portion of the generator and from the upper ends of which steam and water are conducted into a steam and water drum, a water level gauge on the steam and water drum, and means for conducting water from the steam and water drum into the headers, the improvement for preventing starving of the tubes and headers for water when an ample supply of water is present in the steam and water drum which comprises a pres-

sure responsive mechanism connected by a conduit into the steam and water drum and having a movable indicator member responsive to the pressure in the steam and water drum and which indicates the pressure therein, said mechanism also being connected by a conduit into a header in the lower portion of the generator and having a second movable indicator member which is responsive to the pressure in the header and which indicates the pressure in the said header, a control circuit for controlling the generator and having separate means connected respectively to said members, and means responsive to the movement of the second movable member to a pressure indication within a predetermined pressure of that indicated by the first movable member for energizing the control circuit, whereby the generator is maintained at a safe steaming capacity with an ample water supply for the steaming tubes.

2. An apparatus as defined by claim 1 in which the control circuit includes an alarm for indicating that steaming tubes are being starved for water.

3. In an apparatus for controlling the capacity of steam generators having combustion chamber walls which include bare radiation steaming tubes connected into headers in the lower portion of the generator and from the upper ends of which steam and water are conducted into a steam and water drum, a water drum in the lower portion of the generator, and means for conducting water from the steam and water drum into the water drum and from there into the headers, the improvement for preventing starving of the tubes and headers for water when an ample supply of water is present in the steam and water drum which comprises a pressure responsive mechanism connected by a conduit into the steam and water drum and having a movable member responsive to the pressure maintained therein, said mechanism also being connected by a separate conduit into a header in the lower portion of the generator and having a second movable member adjacent the first which is responsive to the pressure in the said header, a control circuit for controlling the generator and having separate means connected respectively to said members, and means responsive to the movement of the second movable member toward the first to a predetermined extent for energizing the control circuit, whereby the generator is maintained at a safe steaming capacity and starving of the tubes for water is prevented.

4. A generator as defined by claim 3 in which the control circuit includes an alarm to warn of an approaching lack of water in said header.

5. An apparatus as defined by claim 3 in which said circuit includes a generator capacity reducing control adapted to be energized in response to a pressure drop in said header below a predetermined normal pressure with respect to that in the steam and water drum.

6. An apparatus as defined by claim 3 in which means is provided for selectively connecting said mechanism into a plurality of the headers in the lower part of the generator.

7. In an apparatus for controlling the capacity of large steam generators having combustion chamber walls which include long upright bare radiation steaming tubes connected into headers in the lower portion of the generator and from the upper ends of which steam and water are conducted into a steam and water drum substantially above the headers, and means for con-

ducting water from the steam and water drum through a downcomer and into the headers, the improvement for preventing starving of the tubes and headers for water when an ample supply of water is present in the steam and water drum which comprises a pressure responsive mechanism connected by a conduit into the upper portion of the steam and water drum and having a movable member responsive to and which is arranged to indicate the normal pressure therein, means including a conduit connecting said mechanism into a header in the lower portion of the generator, said mechanism having a second movable member which is responsive to and which is arranged to indicate the pressure in the said header, a control for the generator, and means connected to said control and responsive to the movement of the second movable member to a predetermined pressure lower than its normal pressure with respect to 20 the normal pressure indicated by the first mov-

able member for energizing the control whereby the generator is maintained at a safe steaming capacity for preventing starvation of the header for water when ample water is present in the steam and water drum.

8. An apparatus as claimed in claim 1 in which said control circuit includes an electrical circuit, an electrical contact carried by said members in opposed relation, and wires respectively connecting said contacts into the electrical circuit.
